RICHARD H. PASCALL, OF PORTLAND, CONNECTICUT, ASSIGNOR TO THE PICKERING GOVERNOR COMPANY, OF PORTLAND, CONNECTICUT, A CORPORATION OF CONNECTICUT.

GOVERNOR FOR ENGINES.

No. 815,114.

Specification of Letters Patent.

Patented March 13, 1906.

Application filed October 7, 1905. Serial No. 281,778.

To all whom it may concern:

Be it known that I, RICHARD H. PASCALL, a citizen of the United States of America, residing at Portland, in the county of Middlesex and State of Connecticut, have invented certain new and useful Improvements in Governors for Engines, &c., of which the following is a specification.

My invention relates particularly to governors, and is designed to provide means for adjusting the engine speed by manipulation of the valve quite independently of the governor. The usual method of doing this was to introduce mechanism which was connected with the valve-stem and by means of which the resistance of the valve to the action of the governor could be varied; but these devices were capable of providing for but a small variation of the normal engine speed, and modern practice requires a much wider range. It is to meet this demand that my invention has been produced.

Another object of my invention relates to the manner of mounting the springs in the governor-head.

In the drawings, Figure 1 is a perspective elevation of a governor embodying my invention with some parts broken away and others shown in section for purposes of illustration. Fig. 2 is a detail view showing my method of attaching the springs. Fig. 3 is a detail perspective view of the upper part of the spindle and of the sleeve-nut. Fig. 4 is a view of the end face of the adjusting-rod, showing the engaging points. Fig. 5 is a perspective view of the coupling. Fig. 6 is a sectional view of the same.

Referring to the drawings, *a* represents the shell of the valve, *b* the valve proper, and *c* the valve-stem. To the shell of the valve is secured the frame *d*, provided with the spindle *e*, on which the governor *f* is rotatably mounted. The governor illustrated is of the type having upper and lower sleeves *f'* *f''*, fitting on the spindle and provided with flanges *f¹⁰* *f²⁰*, to which the ends of the ball-carrying springs are secured. The top flange *f¹⁰* has a threaded boss *f¹¹* to receive a bonnet-nut, as later described.

50 I use a short valve-stem *c*, which is secured in any suitable manner to a coupling-piece *g*. Passing down through the spindle *e* is an adjusting-rod *h*, which is threaded to engage

threads in a sleeve-nut *i*, which is splined to the spindle *e*, leaving it free to move lengthwise with respect thereto, but holding it against rotation. The adjusting-rod has an operating-handle, as the knurled head *h'*. Its lower end fits into a recess in the coupling *g*, and the face of this lower end is provided with engaging points *h²*, which coöperate with similar points at the base of the socket or on the part with which the adjusting-rod contacts in order to prevent the accidental turning of this adjusting-rod. These engaging points are not deep enough, however, to prevent the ready turning of the rod by the knurled head *h'*.

A bonnet-nut *j* incloses the sleeve-nut *i* and is screwed to the threaded boss *f¹¹*. This bonnet-nut is shouldered, as at *l²*, to engage a shoulder on the sleeve-nut *i*, so that as the governor-cap moves downwardly under the centrifugal action of the weights the sleeve-nut and the adjusting-rod will be carried with it, this downward movement being transferred to the valve-stem through the coupling *g* to cause a corresponding movement of the valve. A thin metallic washer *k* is interposed between these shoulders in order to allow for the free rotation of the bonnet-nut about the sleeve-nut. It is to be clearly understood that the valve-stem *c*, the coupling *g*, the spindle *e*, the sleeve-nut *i*, and the adjusting-rod *h* are non-rotatable.

A spring *m* is mounted on a spindle which carries a dog *n*, which engages shoulders on the coupling *g*. Means are provided, as the worm-gear *m'*, for winding up this spring, causing the dog to exert an upward pressure on the coupling. This spring tends to lift the valve, and its force must be overcome by the governor in order to close the valve.

The operation of the device is as follows, it being understood that the governor is driven from the main shaft of the engine through the pulley *o* and the beveled gears *p*: The valve is set to meet ordinary conditions of use by winding up the torsional spring *m* until it exerts an upward pressure on the valve-stem, which will be counterbalanced by the centrifugal force of the rotating governor-head to keep the valve open to a proper extent and maintain the speed of the engine. If for unusual causes the speed of the engine is to be increased, or it is desired to increase the

speed of the engine during certain hours of the day, the adjusting-rod is unscrewed from the sleeve-nut i , permitting the valve to be raised under the influence of the spring, giving it a greater distance to travel in controlling the admission of steam. In consequence the engine speed must increase. The speed of the engine is diminished by screwing down the adjusting-rod and closing the valve independently of the governor action. It is to be noted that all parts of this adjusting device are non-rotatable and in consequence that it cannot be affected in any way by the rotation of the governor-head; also, that the adjustment can be freely made while the governor is in operation, that it is simple in its operation, inexpensive in construction, and extremely effective in accomplishing the results for which it is designed.

20 Another feature of the invention resides in the manner of attaching the weight-springs to the top and base flanges of the governor. These flanges $f^{10} f^{20}$ have slots t milled in them, the bottoms of which are at angles to their axes. The springs $u u$ at each end are secured firmly in these slots flat against the bottoms, with the result that when the governor is at rest the springs are on an even continuous curve from the top to the bottom flange. When the governor is in action, the springs of course are curved still more; but under ordinary conditions the curve is substantially a continuous even one from flange to flange, resulting in a more continuously uniform action of the governor-head. In assembling these parts the springs are secured in place in the grooves, the bands v are shrunk onto the flanges, and the space over each spring is filled by pouring in a molten metal, as lead, (seen at w .) Thus when the whole structure is assembled the parts are solidly bound together and an advantageous construction is provided.

I claim as my invention—

45 1. A governor for steam-engines and the like comprising the valve-chamber, the valve and its stem, the governor-head, and means for adjusting the valve vertically independently of the governor-head comprising a non-rotary nut and an adjusting-rod threaded into said nut with its end connected with the end of the valve-stem, and connections between the top flange of the governor-head and said adjusting-rod to cause them to move together vertically, as and for the purposes specified.

50 2. A governor for steam-engines and the like comprising the valve-chamber, the valve and its stem, yielding means normally exerting an upward pressure on said valve, the governor-head, and means for adjusting the valve vertically independently of the gov-

ernor-head comprising a non-rotary nut and an adjusting-rod threaded into said nut with its end connected with the end of the valve-stem, and connections between the top flange of the governor-head and said adjusting-rod to cause them to move together vertically, as and for the purposes specified.

65 3. A governor for steam-engines and the like comprising the valve-chamber, the valve and its stem, yielding means normally exerting an upward pressure on said valve, the governor-head, and means for adjusting the valve vertically independently of the governor-head comprising a non-rotary nut, an adjusting-rod threaded into said nut with its end connected with the end of said valve-stem, and a bonnet-nut secured to the top flange of the governor-head and having engagement with said nut whereby said nut takes its vertical movement from the vertical movement of said governor-cap.

70 4. A governor for steam-engines and the like comprising the valve-chamber, the valve and its stem, yielding means normally exerting an upward pressure on said valve, the governor-head, and means for adjusting the valve vertically independently of the governor-head comprising a nut splined to a non-rotary part of the governor and adapted for lengthwise movement thereof, an adjusting-rod threaded into said nut with its end connected with said valve-stem, and connections between said nut and the top flange of the governor-head to cause them to travel together vertically.

75 5. In a governor the cap and base-rings, and two or more springs secured thereto, the plane of attachment of said spring to said rings being angularly disposed with reference to the axes of the governor.

80 6. In a governor the cap and its rings having peripheral slots the bottoms of which are angularly disposed with relation to the axes of the governor, and springs having their ends firmly secured to the bottoms of said slots, and weights attached to said springs.

85 7. A governor for steam-engines and the like comprising a valve-chamber, a valve and its stem, a governor-head, and means for adjusting the valve vertically independently of the governor-head comprising an adjusting-rod threaded in a non-rotary part with its end connected with the end of said valve-stem, and engaging points on the end of said adjusting-rod.

90 In testimony whereof I affix my signature in presence of two witnesses.
